LIZZIE FRITCH, OF SCHABERG, ARKANSAS.

HAT-PIN PROTECTOR.

1,277,565.

Specification of Letters Patent.

Patented Sept. 3, 1918.

Application filed September 24, 1917. Serial No. 192,989.

To all whom it may concern:

Be it known that I, LIZZIE FRITCH, a citizen of the United States, residing at Schaberg, in the county of Crawford and State 5 of Arkansas, have invented certain new and useful Improvements in Hat-Pin Protectors, of which the following is a specification.

This invention relates to hat pin protectors and it more particularly relates to an improved fastening device for preventing the loss of the hat pin.

One of the objects is to provide an improved form of hat pin, and appropriate 15 fastening means therefor, in such relation that the head of the hat pin combines with a portion of the fastener to form an ornament on the exterior surface of a hat to which the device is applied.

20 Another object of the invention is to provide a device of this character which is thoroughly efficient and practical for the purpose of preventing the loss of the hat pin, and which enables the wearer to employ a hat pin of no greater length than is actually necessary to pass through the 25 crown of the hat, thereby obviating the danger which is well known when excessively long hat pins are employed.

30 Another object is to provide a device of this character which is capable of being quickly and easily attached to hats of various styles and sizes and which may be quickly and easily detached therefrom, so as 35 to apply it to another hat.

Another object is to provide a device of this character which is not materially detrimental to a hat to which it is attached and from which it is removed.

40 Another object is to provide a device of this character which is simple of structure, economical in manufacturing, and thoroughly practical and effective in use.

45 Other objects and advantages may appear to those who read the following detailed description and claims, in connection with the appended drawings in which:

50 Figure 1 is a perspective view of my invention, shown as applied to a hat, said hat being merely indicated in broken lines:

Fig. 2 is a vertical sectional view taken on the line 2—2 of Fig. 3, the fragment of hat which is shown in the latter figure being eliminated from Fig. 2: and

55 Fig. 3 is a sectional view taken substantially on line 3—3 of Fig. 2.

Referring to these drawings in detail, in which similar reference characters correspond with similar parts throughout the several views, the hat is represented by the letter A, and is not described in detail, its specific construction being no part of the present invention.

The hat pin comprises a shank or pin element 10, pointed at 11 and enlarged at 12, the enlargement 12 being screw-threaded for engagement with a nut 13 of the fastening element which is somewhat in the form of an ordinary safety pin being provided with the usual spring coil 14, the usual point 15, and the usual hook 16. However, the fastening element differs from the ordinary safety pin, in that it is united with the nut 13. The fastening element is connected to a plate or ornament 17, which is illustrated as being angular in outline, but which may be of any preferred ornamental shape. Securing elements 18 are provided for connecting the fastening element permanently on the plate 17, being apertured for the reception of the back of the fastening element which comprises the nut 13. The elements 18 may be primarily formed as upstanding prongs capable of being bent over the back 19 of the fastening element. However, any appropriate fastening means may be employed for connecting the fastening element to the plate 17. The plate 17 is provided with an aperture 20 which registers with the screw-threaded aperture of the nut 13, being sufficiently large to allow the threaded element 12 to pass freely therethrough. The pin-tongue 21 is curved slightly, as shown in Fig. 2, so as to allow the pin 10 to pass thereby without interference.

95 The hat pin is provided with an ornamental head 22 which also serves as a manipulative element whereby the threaded portion 12 may be screwed tightly into the nut 13, so that the shoulder 23, of the head 22 bears and binds against the plate 17, and co-operates with the nut 13 for holding the pin 10 in its operative position through the hat.

100 In applying this device to a hat, the pin prong 21 is first passed into and out of the side of the hat, as shown in Fig. 3, while the pin 10 is disengaged from the nut 13. The fastener being thus properly positioned, the hat pin is next forced through the aperture 20, the nut 13 and the adjacent portion of the hat until the screw-threaded portion 12

has reached said nut; whereupon the user rotates the head 22, thereby screwing the element 12 into the nut 13 and forcing a portion of the element 12 through the side 5 of the hat. Therefore, the contiguous fibers or constituents of the hat are forced apart by the screw element 12, against resistance, and said constituents continually exert a binding effect upon the screw-threads, so as 10 to help the elements 13, 20 and 23 to prevent accidental rotation of the hat pin. However, such action is easily overcome by the hand of the wearer, in rotating the head 22, when desired to remove the hat pin.

15 From the foregoing it will be seen that I have provided a device of this character which is extremely useful and practicable, and which it is believed will become popular and meet with great commercial success.

20 I claim as my invention:

1. The combination of a hat pin provided with a screw-thread element, a nut engageable with said screw-thread element, and means coöperative with said nut for securing 25 said hat pin removably to the crown of the hat.

2. The combination of a pin provided with a point at one end and with a screw-thread at its other end, a second pin crossing the first said pin, and a nut connected 30 with said second pin and engageable with

the screw-threaded element of the first said pin.

3. The combination of a pin provided with a screw-thread, a hat through one side 35 of which said screw-thread normally extends in binding relation, a second pin extending in and out through said side of the hat and crossing the first said pin, and means co-operative with said screw-thread and with 40 the second said pin for holding the first said pin against accidental displacement from said hat.

4. The combination of a hat pin provided with a head at one end and with a screw 45 thread adjacent to said head, a second pin crossing the first said pin, a nut united with said second pin and engageable with said screw thread, and an ornament normally disposed between said head and said nut and 50 being coöperative with the latter for holding the first said pin in such relation to the second said pin as to tend to prevent displacement of the first said pin with relation to the second said pin. 55

In testimony whereof I affix my signature in presence of two witnesses.

LIZZIE FRITCH.
